UNITED STATES PATENT OFFICE.

PHILIP TELL DODGE, OF WASHINGTON, DISTRICT OF COLUMBIA, ASSIGNEE TO MERR-
CENTHALER LINOTYPE COMPANY, A CORPORATION OF NEW YORK

TYPOGRAPHICAL MACHINE.

1,111,080.

Specification of Letters Patent. Patented Sept. 22, 1914.

Application filed March 29, 1912. Serial No. 687,011.

To all whom it may concern:

Be it known that I, PHILIP T. Dodge, a citizen of the United States, and a resident of Washington, in the District of Columbia, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine in the order in which their characters are to appear in print, and then assembled in line, the composed line transferred to the face of a slotted mold, the mold filled with molten metal to form a slug or linotype against the matrices which produce the type characters thereon, and the matrices thereafter elevated and returned through a distributing mechanism to the magazine from which they started.

At the present day it is a common practice in the art, more particularly for advertising purposes, to employ in connection with parallel lines of print, large figures or characters which extend over and occupy space on two or more such lines, and commonly known as "two-line", "plural-line", etc., characters. When such printing is effected by the use of slugs or linotypes bearing lines of characters thereon, it is sometimes the custom to form one portion of the large or extended character on one slug, and other portions on other slugs. This is effected by the use of a plurality of complementary matrices which are employed respectively in the production of the several slugs, one slug being cast from a composed line of matrices, and the second or complementary slug being thereafter cast from a second line of matrices complementary to the first. Heretofore such matrices have not been carried in the magazine or represented on the keyboard, but have been ordinarily set into the line by hand, as sorts or the like.

The aim of my invention is to provide for the handling of the complementary matrices, representing the several parts of a single extended figure or character, in an ordinary linotype machine, without increasing the size of its magazine or the number of its keys, and without requiring special attention or loss of time on the part of the operator.

To this end I arrange the several complementary matrices, which form a single extended character, to run in one and the same magazine channel, (and therefore provide them with the same distributing combination,) so that for example, if the operator desires to produce the two-line figure 3, he first touches the 3-key in the keyboard, whereupon the matrix for producing the upper half of the character will be set into the line and a slug subsequently produced therefrom bearing the upper portion of the character. In due time and when composing the matrices for the next slug, the operator again touches the 3-key, whereupon the second matrix, for producing the lower half of the figure, is delivered, and the lower portion of the character consequently formed on the second slug. It will be understood that the second matrix is set into the line in the same relative position as the first one, so that the two parts of the character on the successive slugs will register when brought together. Of course, any desired number of pairs of matrices for producing the same figure or character may be placed in the same magazine channel. It will be perceived that I am thus able to produce these extended figures without special attention or action on the part of the operator and without increasing the number of the magazine channels or in any other manner changing the machine.

In the accompanying drawing I have shown my invention in preferred form by way of example, and as applied to a linotype machine, but obviously many changes and variations may be made therein, and in its mode of application, without departing from its scope; and, generally speaking, I desire it to be understood that I do not limit myself to any specific form or embodiment except in so far as such limitations are specified in the claims.

Referring to the drawing: Figure 1 represents two lines of print having two-line characters such as I aim to secure; Fig. 2 illustrates the linotypes or slugs for producing such print; Fig. 3 shows a pair of complementary two-line matrices, adapted for use in the commercial linotype machine; Fig. 4 is a diagram of the machine, illustrating the manner in which the matrices may be used; and Fig. 5 illustrates the arrangement of the matrices in a channel.

Referring to the drawing, the two linotypes or slugs A and B each bear a line of complete type thereon, and in addition the upper and lower parts of the two-line figures, 2 and 3. To produce the separate portions of such characters I employ two sets of matrices C and D similar in their general construction to those commonly used and known in the art. Each of the matrices C contains the depression *c* representing the upper half of the figure 3, while each of the matrices D contains the depression *d* representing the lower or complementary half thereof. Although the matrices C and D are intended to produce different character portions, they are formed with distributing teeth or combinations *e*, which are exactly alike, so that both will be delivered by the distributor into one and the same magazine channel M. The manner in which such matrices are handled will be understood by reference to Fig. 4, wherein is illustrated the magazine E containing the matrices, the keyboard F having finger keys to represent the various characters and connected with escapements (not shown) to deliver the selected matrices, and the inclined belt G which receives the discharged matrices, and by which they are transferred successively to the assembler H. When the line is completely composed, it is transferred in the direction of the arrows, first upwardly, then laterally, and then downwardly, to the casting mechanism I, where the slugs are produced, and thereafter upwardly, then laterally, then upwardly, and again laterally, to the distributor J, which receives the matrices and delivers them one at a time into the upper ends of the magazine channels from which they were originally discharged. These parts and operations are or may be like those disclosed in the before-mentioned Mergenthaler patent.

It will be observed, in view of the fact that the matrices for the first line are distributed in advance of the matrices for the second line, that the complementary matrices C and D are returned to the channel M in the same order in which they were delivered therefrom, so that the operator desiring to use the matrices again in successive lines of composition has merely to touch the same finger key in the keyboard, once for each line.

By way of illustration and preferred example, I have represented the matrices as arranged for producing two-line letters, or letters composed of two parts, but it will be understood that this principle may be employed in connection with figures, letters, or other characters, which are extended across three, four, or more slugs, by using the corresponding number of matrices, each bearing the appropriate matrix portion or section.

Similarly it will be apparent that my in-

vention may be adapted to typographical machines other than of the line-casting variety, such for instance as machines employing or producing plural-line type similarly extending over any desired number of successive lines. In this connection, the principal requirement is that the type or matrices, which coöperate in producing a composite or sectional character in successive lines, shall be arranged for delivery in the proper order by a single key. As previously pointed out, many modifications and variations will suggest themselves to those skilled in the art and still be comprised within the spirit of my invention.

Having thus described my invention, its construction and mode of operation, what I claim and desire to secure by Letters Patent of the United States is as follows:

1. In a typographical machine, the combination of a plurality of sets of type or matrices, those of one set containing the upper portion of an extended character, and those of another set containing the complementary lower portion of such character, and a single selecting means therefor, the successive operation of which delivers the type or matrices consecutively from the several sets.

2. In a typographical machine, the combination of a plurality of sets of type or matrices, those of one set containing the upper portion of an extended character, and those of another set containing the complementary lower portion of such character, and a single storing means therefor, whereby the type or matrices of the several sets are stored together in proper consecutive order.

3. In a typographical machine, the combination of a plurality of sets of type or matrices, those of one set containing the upper portion of an extended character, and those of another set containing the complementary lower portion of such character, the said type or matrices being all provided with the same distributing combination, and distributing devices, whereby the type or matrices of the several sets are all released at the same point.

4. In a typographical machine, the combination of a plurality of sets of matrices, those of one set containing the upper portion of an extended character, and those of another set containing the complementary lower portion of such character, a single storing means wherein the type or matrices of the several sets are arranged consecutively, and distributing devices to deliver the type or matrices of the several sets to the storing means in proper consecutive order.

5. In a typographical machine, the combination of a plurality of sets of matrices, those of one set containing the upper portion of an extended character, and those of another set containing the complementary lower portion of such character, a single

means for storing the matrices of the several sets in consecutive order, a single selecting means to deliver the type or matrices successively therefrom, and distributing devices to restore the type or matrices to the single storing means in proper consecutive order.

6. In a typographical machine, the combination of a magazine channel and a series of matrices bearing complementary portions of 10 a transversely divided character, and ar-

ranged alternately therein, said channel containing the same number of matrices of each kind, for the purpose set forth.

In testimony whereof I hereunto set my hand this 21st day of March, 1912, in the presence of two attesting witnesses.

PHILIP TELL DODGE.
